UNITED STATES PATENT OFFICE.

ARTHUR L. FOLEY, OF BLOOMINGTON, INDIANA, ASSIGNOR TO GEORGE FABYAN, OF RIVERBANK, ILLINOIS.

HORN FOR SOUND INSTRUMENTS.

Application filed March 3, 1923. Serial No. 622,472.

To all whom it may concern:

Be it known that I, ARTHUR L. FOLEY, a citizen of the United States, and a resident of Bloomington, in the county of Monroe and State of Indiana, have invented certain new and useful Improvements in a Horn for Sound Instruments; and I do hereby declare that the following is a full, clear, and exact description of the same, reference being had to the accompanying drawings, and to the numerals of reference marked thereon, which form a part of this specification.

In many instruments dealing with sound, a horn is used as a sound amplifier, either to increase the total intensity or the intensity in a given direction, of the sound produced by the instrument itself, or to increase the sound energy received upon a small surface placed at or near the small end of a horn. In both such cases, the horn is apt to cause a considerable loss of sound energy by undesirable reflections. This is best illustrated in the case of an incoming sound. The sound reflected from one side of the horn near the mouth thereof either emerges directly through the mouth, or crosses the horn and being reflected a second time from the opposite wall, then escapes through the mouth. Diffraction and retarding actions of various sorts also cause loss of sound energy in horns heretofore used.

It is an object of the present invention to produce a horn that shall avoid or diminish these losses.

It is a further object of this invention to provide a horn that will concentrate approaching sound without reflecting back into the atmosphere any considerable portion of the sound received.

It is a further object of this invention to combine with an outer larger horn one or more smaller inner horns in such a manner as to give the combination a higher efficiency as a sound condensing instrument than can be obtained with any single horn of like aperture.

Other and further important objects of this invention will be apparent from the disclosures in the accompanying drawings and the following specification.

The invention (in a preferred form) is illustrated in the drawings and hereinafter more fully described.

On the drawings:

Figure 1 is a longitudinal section showing one form of my invention.

Figures 2 to 5 are similar sections showing modified forms.

As shown on the drawings:

The external horn 1 in Figure 1 is of the conventional flower shape, that is to say, instead of being strictly conical, the sides flare more and more as the bell end 2 of the horn is approached, while at the small end 3, the horn either becomes strictly conical or terminates in a cylindrical tube.

In carrying out my invention, I place within the horn 1 and coaxial with it another horn 4 which is of somewhat the same general shape. The bell end 5 of this horn is within the bell end 2 of the horn 1, not only in the sense of being surrounded by it, but also in the sense of being farther toward the interior; that is, the horn 4 is not as long as the horn 1 and a portion of the difference in length is between the bell end 5 and the bell end 2. The remainder of the difference in length is between the small end 3 of the horn 1 and the small end 6 of the horn 4. The small end 6 is therefore in both senses within the small end of the horn 1.

The several horns may be supported in any desired manner. Preferably, the supports should be of a sort that interfere as little as possible with the passage of sound through the horns. One form of support is by the use of radial strips of sheet metal placed with the plane of the strips parallel to the common axis of the horns.

Although the horn 1 and the horn 4 are both described as of the same general shape, the relation between the curve of the wall of one horn and that of the other is not arbitrary. The shape of the horn 1 having been decided, the horn 4 will be so shaped that sound reflected from the protruding part of the bell end of the horn 1 and arriving at the external surface of the bell end 5 of the horn 4 will be reflected in a direction that slopes toward the small end of the horn 1 as it approaches said horn. When the sound is again reflected, from a point on the horn 1 nearer the small end, and so again arrives at the exterior surface of the horn 4, it is again reflected at such an angle that it will make further progress toward the small end 3 of the horn 1. In order to insure this relation between the several re-

2
flections of the sound, the wall of the horn 1 and the wall of the horn 4 are not parallel but they approach each other as they approach the small end of the horn 1, and the curve of each wall is designed to accomplish this. In this way, not only is reflection outward prevented, but the sound is confined within a continually narrowing space so that the intensity of the sound vibration is necessarily increased.

Sound arriving from outside the horn against the inner face of the bell 5 is similarly reflected by a third horn 7 within the horn 4. If desired, still further horns inside 15 of one another may be added. The bell end of each horn is inside of the bell end of the next larger horn; that is, it is to the left of said end as illustrated in Figure 1. The small end of each horn is inside the small 20 end of the next larger horn; that is, it is to the right of said end, as illustrated in Figure 1.

In the form illustrated in Figure 2, I have shown a conical horn 10 with interior nested 25 horns 11 and 12. In Figure 3, I have shown an approximately parabolic horn 13 with similar nested horns 14 within it. In Figure 4, I have shown a horn 15 of double curvature, the part nearest the bell being 30 convex outward. Similar horns 16 are nested within the horn 15. In Figure 5, I have shown a horn 17 with nested horns 18 which are also of double curvature but convex in the direction opposite to that illustrated in Figure 4. These illustrations serve 35 to show that the invention is applicable to horns of many shapes. The shape of the external horn is not entirely arbitrary but is determined by the use to which the horn is 40 to be put, by its length, aperture, and small end diameter, by the distance to the sound source, by the extent it is desired to make use of the horn as a resonator, and by the pitch and quality of the sound to be amplified or condensed. The inner horns in each 45 case have somewhat the same general form as the outer one but are not mere copies on a smaller scale. They are designed from the shape of the outer horn, as explained in 50 describing Figure 1.

When the horn is used to amplify the sound from a sound-emitting instrument instead of to concentrate sound for a sound-

receiving instrument, the several horns may 55 be, but need not be, arranged along a common axis, and the large ends of the several horns preferably are, but need not be, in one plane. Their size and shape is determined chiefly by the sounds which they are 60 to reinforce, and with which they must therefore resonate.

In the operation of the device, sound from outside the instrument arrives at the bell end and is received upon the inner surfaces of the several horns. These reflect the sound to 65 the outer surfaces of the horns next within, which reflect the sound again to the inner surfaces of the surrounding horns, but nearer the small end thereof. This process is repeated until the sound emerges at the small 70 end of the horn and arrives at the ear or other sound-receiving instrument. No reflections toward the bell end of the horn occur and so no sound is lost by being reflected back into the atmosphere.

When the horn is used to amplify the sound from a sound-emitting instrument, instead of to concentrate sound for a sound-receiving instrument, the reflections will always be toward the bell end of the horn, 80 and so no energy is lost by any sound being reflected back into the sound producing instrument.

I am aware that numerous details of construction may be varied through a wide 85 range without departing from the principles of this invention, and I therefore do not purpose limiting the patent granted, otherwise than necessitated by the prior art.

I claim as my invention:

In a sound-conveying device, a plurality of nested spaced horns of successively diminishing length, the shorter being inside and terminating as to both ends of each horn short of the corresponding end of the next 95 outer horn, the surfaces of said horns approaching one another toward the small ends thereof, whereby opposed portions of the surfaces of adjacent horns are non-parallel.

In testimony whereof I have hereunto subscribed my name in the presence of two 100 subscribing witnesses.

ARTHUR L. FOLEY.
